BLOWER INLET CONTROL DEVICE

Ewald Trumpa, Huntington, N. Y.

Application February 28, 1948, Serial No. 12,062

1 Claim. (Cl. 230—114)

1

This invention relates to air flow control devices and in particular to one used in connection with the oil burner unit of a heating system.

The furnace or boiler with which an oil burner unit is employed is generally located in the cellar of the structure and close to the floor thereof where the coldest air in the house normally is found. A dwelling, used as an example of the application of my invention, may be provided with thermostat controls located in various parts of the house for automatically controlling the operation of the oil burner unit which includes the usual air intake chamber and a fan or blower, the motor, a fuel pump and a control circuit. When the operation of the unit is arrested under influence of the thermostat control, the cold air along the floor of the cellar rushes into the warm fire box of the furnace through the air intake chamber and the blower intake openings. This is due to the difference in the weight of the cold air outside the furnace and the warm air inside the furnace. This inrush of cold air quickly cools the firebox, the burner and the fuel in the latter with the result that, when the unit is again operated under control of the thermostat, it is sluggish and burns an excess of fuel oil in restoring itself to the normal operating condition that prevailed before it was shut down. This periodic curtailment of operation of the unit, as caused by the thermostat or in some instances a manual control, uses an excess of fuel a number of times a day with the result that the aggregate consumption of fuel is greater than should normally be required.

It is an important object of my invention therefore, to provide a means for preserving the heated condition of the interior of the furnace firebox when the oil burner is periodically interrupted in its operation to lower the temperature of the rooms so that a substantial saving in fuel consumption can be obtained; so that when the burner unit is again operated, the fuel oil will bring the firebox up to operating temperature in the quickest period of time; so that by cutting down the time necessary to bring the firebox up to the proper operating temperature, the heating system will be more quickly responsive to the control element and the differences in "on" and "off" times of the burner will result in a further and maximum saving of fuel.

I am aware that dampers have been employed in flue pipes leading away from the furnace for adjusting the flow of air, but these, by their location in the outlet pipe or stack, do not prevent the cold air in the cellar from rushing into the firebox when the fan ceases operation to cut down com-

bustion. Other objects of my invention include the provision of means in association with the oil burner unit itself and connected with the motor and thermostat control circuit so that the air intake to the fan or blower can be automatically controlled in accordance with the operation of the oil burner unit. Still further objects of the invention are the provision of means that can be applied to any existing oil burner unit or can be built into the unit originally; the parts being so arranged that the device may be readily applied at small cost and in most instances without the need of any special equipment or expensive help for the home owner.

15 Various other objects and advantages of the invention will be obvious from the following particular description of my invention which constitutes certain new and useful features of construction and combination of parts hereinafter set forth and claimed and illustrated in the accompanying drawings in which:

15 Figure 1 is a view in side elevation of a typical furnace and oil burner installation as commonly used for the purpose of heating a structure showing the application of my invention thereto.

20 Figure 2 is a diagrammatic view of a circuit used with the installation shown in Figure 1 for operation of the oil burner and an air cut-off device under influence of a thermostat.

25 Figure 3 is a view, partly in section, of the cut-off device shown in the closed position it assumes when the oil burning unit is not operating.

30 Figure 4 is a fragmentary view similar to Figure 3 showing the cut-off device in open position.

35 Figure 5 is a section taken on the line 5—5 of Figure 3 showing the relative arrangement of the air intake openings and cut-off device associated therewith.

40 Figure 6 is a side view of the parts as seen looking toward the right in Figure 3.

45 Figure 7 is an end view of the oil burner unit showing the application to the fan housing of a rotary type cut-off device.

Figure 8 is a side view of a unit, partly in section, showing the use of another form of cut-off device.

50 Figure 9 is a view in end elevation of a unit showing the application of a rotary type cut-off device thereto, and

55 Figure 10 is a side view of the device shown in Figure 9 with some parts omitted for clarity of illustration.

Referring to the drawings in detail, and in particular to Figures 1 through 6, a boiler or furnace of standard type, indicated at 15, is serviced by an oil burner unit 16 including the

usual suction air intake chamber or housing 17, motor driven blower 18 and oil feed pipe 19, through the latter of which fuel is fed to a burner, not shown, but disposed in the well known manner in the firebox of the furnace 15. Various arrangements of the air intake fan are employed, but all have air intake openings through which the air in the cellar is drawn for forced propulsion through the unit to support combustion in the firebox. In one form, the fan housing which is formed to provide air chamber 17 of cylindrical shape, as at 20, is provided with peripherally spaced air intake openings 21 along the under side thereof and in the use of my novel air intake cut-off device, I employ a flap plate 22 which closely conforms in shape with the curved outer surface of housing 17 so that it overlies all of the openings 21 to effectively close the same when the flap plate is closed. The plate is shaped at one end with an outwardly bent flange 23 which is further bent at its opposite ends to provide tabs 24 through which extend a pivot pin 25 fixed at one end in the upper extremity of a bracket 26.

The pin 25 carries a spring 27, the free ends of which engage the outer surface of flap plate 22 and a bracket mounted stud 28, respectively. The bracket is fixed to a solenoid housing 29 as by bolts 30 and the housing may be secured in any suitable manner as by stud screws 31 to any adjacent part of the unit 16. Within the housing 29 there is mounted a solenoid which is included in a circuit 33 connecting the motor 18 and one or more motor controlling thermostats 34 remotely located with reference to the furnace. The core of the solenoid is provided with spaced ears 35 in which a pivot pin 36 is mounted and the outer surface of the plate 22 presents spaced tabs 37 in which a similar pivot pin 38 is journaled. The pins 36 and 37 connect a link 39 with the solenoid and the plate so that when the solenoid is energized by operation of the thermostat to start the motor, the plate 22 is pulled to open position as shown in Figure 4 against the resistance of the spring 27 to uncover the fan housing inlet air openings 21. Ordinarily when the motor ceases operating, the cold air entering the fan housing quickly cooled off the burner and the firebox with the result that a greater amount of fuel had to be burned to attain normal operating conditions after the motor was again started. My flap plate is automatically closed by the action of the spring 27 when the solenoid is deenergized by the breaking of the motor circuit under thermostat control. While the thermostat is used as an example, the circuit could be manually controlled with the same results.

Modifications in the structures of various oil burner units require that air cut-off devices be differently arranged and to this end, as shown in Figure 7, an end wall 40 of a fan air intake housing 41 having radially disposed segmental air intake openings 42 has pivoted thereto as at 43 a disk plate 44 shaped to provide radially disposed segmental air openings 45 and solid portions 46 arranged alternately so that the disk may be revolved to cover and uncover the openings 42 in the wall 40 to control the air intake. The disk plate is provided with extensions 48 to one of which is connected a spring 49 and to the other an operating link 50 which is actuated by the solenoid. The latter may be physically mounted in any suitable manner and included in the motor circuit so that when the motor

stops, the spring 49 will revolve or rotate the disk to bring the solid portions 46 into register with the housing openings 42 to seal the housing against cold outside air. Energization of the solenoid will adjust the disk plate to uncover the openings in the housing and supply air to the unit during operation.

In Figure 8, where the fan housing has an air intake duct opening 50, a circular damper type closure disk may be pivotally mounted within and adjacent the mouth of the duct so that when the disk is in tilted position shown it will admit air and when in horizontal position will close the duct and prevent admission of cold air to the unit. The disk 51 is connected to the solenoid by a link 52 and is moved to closed position by a spring 53 when the solenoid is deenergized.

In Figure 9, use is made of a ring or band type cut off 55 which has close sliding fit about the periphery of the fan air intake housing 56 in which spaced openings 57 are arranged. The band 55 has alternately arranged ports or openings 58 and solid portions 59 which register with the openings 57 to cut off or supply air to the fan or blower. The band has spaced ears 60 at the lateral edges thereof for support of a pin 61 therebetween and to which one end of the solenoid line 62 is connected so that when the solenoid is energized and pulls on the link, the band is rotated enough to uncover the openings 57 which are covered when the solenoid is deenergized by the counter action of a spring 63 which connects a tab 64 on the band with the housing. While I have shown and described a core type solenoid, it will be understood that the term solenoid embraces within its scope any electromagnetic means that may be employed to carry out the purpose of the inventions.

While I have described what I now consider to be a highly desirable embodiment of my invention, it is obvious that many changes in form may be made without departing from the spirit of the invention, and I therefore do not wish to be limited to the exact forms herein shown and described, nor to anything less than the whole of the invention as hereinbefore set forth and as hereinafter claimed.

What I claim as new and desire to secure by Letters Patent is:

The combination with an oil burner housing of a blower and an air intake chamber opening into the blower and having an opening therein for admitting air to the blower from outside the housing, of a bracket fixed to said housing, a pivot pin extending from said bracket, a flap plate shaped to conform to the exterior contour of said housing to fit over and close said opening to the passage of air, said plate being shaped to provide a flange, ears on the flange for mounting the plate pivotally on said pin, a spring mounted on said pivot pin and having its free ends in engagement with the bracket and the flap plate for normally urging the latter toward and against the housing to closed position, a solenoid unit including a housing mounted on said oil burner housing, means for mounting said bracket on said solenoid housing, ears on said plate and a link connecting the core of the solenoid with the ears of the plate whereby the plate will be pulled away from said housing to open position against the resistance of said spring when the solenoid is energized.

EWALD TRUMPA.
